(57) **CLAIM**

The ornamental design for a control switch, as shown and described.

DESCRIPTION

FIG. 1 is a front elevation view of our new design of a control switch according to a first embodiment;

FIG. 2 is a rear elevation view of the design of FIG. 1;

FIG. 3 is a right side elevation view of the design of FIG. 1;

FIG. 4 is a left side elevation view of the design of FIG. 1;

FIG. 5 is a top plan view of the design of FIG. 1;

FIG. 6 is a bottom plan view of the design of FIG. 1;

FIG. 7 is a front and right side perspective view of the design of FIG. 1;

FIG. 8 is a front elevation view of our new design of a control switch according to a second embodiment;

FIG. 9 is a rear elevation view of the design of FIG. 8;

FIG. 10 is a right side elevation view of the design of FIG. 8;

FIG. 11 is a left side elevation view of the design of FIG. 8;

FIG. 12 is a top plan view of the design of FIG. 8;

FIG. 13 is a bottom plan view of the design of FIG. 8; and,

FIG. 14 is a front and right side perspective view of the design of FIG. 8;
